UNITED STATES PATENT OFFICE.

ALFRED B. FOWLER, OF BEVERLY, MASSACHUSETTS, ASSIGNOR TO UNITED SHOE MACHINERY CORPORATION, OF PATERSON, NEW JERSEY, A CORPORATION OF NEW JERSEY.

STOP MECHANISM.

Application filed February 3, 1919. Serial No. 274,608.

To all whom it may concern:

Be it known that I, ALFRED B. FOWLER, a citizen of the United States, residing at Beverly, in the county of Essex and State of Massachusetts, have invented certain new and useful Improvements in Stop Mechanisms; and I do hereby declare the following to be a full, clear, and exact description of the invention, such as will enable others skilled in the art to which it appertains to make and use the same.

The present invention relates to mechanisms for stopping a machine with the driven parts in a predetermined position.

One of the objects of the invention is to provide a novel and improved stop mechanism which is especially adapted for use in machines wherein it is desirable to render certain parts or devices thereof active for a predetermined interval in the final cycle of operations. A machine of this type is the inseam shoe sewing machine illustrated and described in applicant's copending application, Serial No. 254,104, filed Sept. 14, 1918, wherein thread cutting and holding devices are employed that are rendered active for a predetermined interval in the final cycle of operations of the machine.

To this end a feature of the invention contemplates the provision of means under the control of the operator for throwing out the driving mechanism of a machine at a predetermined point in a cycle of operations, and means for stopping the rotation of the driven parts of the machine a predetermined interval after the driving mechanism is thrown out. In the preferred embodiment of the invention, after the driving mechanism is thrown out the machine is driven by its own momentum for a predetermined interval before the means for stopping the machine is rendered active, but this specific mode of operation is not essential to the broader features of the invention.

Another object of the invention is to provide a novel and improved mechanism which will operate efficiently and uniformly in

stopping the driven parts of machine irrespective of the speed thereof when the mechanism comes into action.

To this end the invention contemplates the provision of means under the control of the operator for throwing out the driving mechanism of a machine at a point in a cycle of operations dependent upon the speed of the machine.

Other features of the invention consist in certain constructions, combinations and arrangements of parts hereafter described and claimed, the advantages of which will be obvious to those skilled in the art.

The several features of the present invention will be understood from the following detailed description and the accompanying drawings in which:

Figure 1 is a vertical longitudinal section through a stop mechanism embodying the features of the present invention in their preferred form; Fig. 2 is a transverse vertical section taken on the line 2—2 of Fig. 1.

In the drawings, the invention is shown embodied in a mechanism for driving and stopping a shaft 6 from which the operating mechanism of a sewing or other machine may be driven. The shaft 6 is driven by means of a friction clutch face 8, formed on a clutch member 10 that is splined on the shaft, when this clutch face is in engagement with a clutch face 12 on the interior of a driving pulley 14, as shown in Fig. 1. This driving pulley is mounted to turn loosely on a fixed bushing 16 surrounding the shaft and is provided with a hub 18 adapted to engage a roll thrust bearing 20 when the driving pulley is forced sufficiently toward the right by engagement of the clutch faces 8 and 12. The clutch member 10 is provided with a grooved collar 22 that is engaged by a clutch shifting yoke 24 pinned on a horizontal rock shaft 26. The shaft 26 has a horizontally extending arm 28 secured to one end thereof, which is connected to a treadle 29 by a rod 33. By depressing the arm 28 by means of the treadle 29 and rod 33 the clutch

2

member 10 is shifted to the right to engage the clutch faces 8 and 12 and when the arm 28 is released by removing the pressure on the treadle 29, a spring 35 acting on the arm 28 through the rod 33 tends to move the clutch member 10 to the left to bring a friction brake face 30 on the clutch member into engagement with a cooperating face 31 on the frame of the machine.

10 After the release of the arm 28, the movement of the clutch member 10 is controlled by two cams, both of which are formed on a disk 32 which is mounted on the shaft 6. When the arm 28 is depressed to bring the driving clutch faces into engagement, a projection 44 on the rock shaft 26 is moved upwardly, so that a lug 46 on the dependent arm of a latch lever 48, pivoted at 50, is drawn beneath the lug by a spring 52 attached to the lower end of the latch lever. This latch lever locks the rock shaft against a sufficient backward movement to entirely disengage the driving clutch faces. The latch lever 48 is engaged by one of the cams on the disk 32 during each revolution of the shaft 6, so that at a certain point in each cycle of operations of the machine, the rock shaft 26 is released and, unless held by the operator, through the medium of the arm 28, can move in a direction to disengage the driving clutch faces. This cam is indicated at 54. While the machine is running there is sufficient play between the lug 46 on the latch lever 48 and the lug 44 on 46 on the rock shaft 26 to allow the driving clutch to be so controlled by the operator through the arm 28 as to vary the speed of the shaft 6. When the operator releases the arm 28, the spring connected therewith rocks the shaft 26 so that the lug 44 engages the lug 46, but at this time there is sufficient friction exerted between the driving clutch faces to drive the shaft 6 until the latch lever is operated by the cam 54. Such operation of the latch lever releases the rock shaft 26 and allows the clutch member 10 to move further towards the left, so as to entirely disengage the driving clutch faces.

45 The shaft 6 now continues to rotate under its own momentum. At this time the braking surface 30 is held out of engagement with the cooperating surface 31 on the frame by means of the second cam 56 on the disk 32, which cam is engaged by a roll 58 on the upper end of an arm 60 adjustably but rigidly fixed on the clutch operating yoke 24. A predetermined number of degrees of rotation after the cam 54 has operated to release the latch through the lever 48, the cam 56 allows the clutch member 10 to move so as to bring the braking surface 30 against the cooperating braking surface 31 on the frame of the machine and stop the shaft.

50 A coiled spring 62 surrounds a hub of the driving pulley 14 and is interposed be-

tween the web of the pulley and the thrust bearing 20. The function of this spring is to keep the driving clutch faces in engagement after the operator releases the treadle and until the latch lever 48 is operated. The movement of the driving pulley to the left under the action of the spring 62 is limited by a stop collar 63 on the shaft 6.

55 It is evident that the duration of the period of engagement of the braking surfaces 30 and 31 before the shaft 6 is brought to rest is dependent upon the speed of the shaft when the engagement of the braking surfaces is initiated. Accordingly, in order to stop the shaft at a uniform or definite point in its rotation, the start of the period of engagement of the braking surfaces must occur at a point in the rotation of the shaft dependent upon the speed thereof at this time. To this end, in the illustrated machine, means are provided to vary the timing of the cams 54 and 56 in accordance with the speed of the shaft, which cams control the engagement of the braking surfaces as hereinbefore described. The cam disk 32, which carries the cams 54 and 56, is loosely mounted on the shaft 6 and its position on the shaft is determined by two centrifugal governor arms 64 pivoted on studs 66 that project from a hand wheel 68 secured to one end of the shaft 6. The free ends of the governor arms 64 are connected by links 70 to the cam disk 32. The governor arms are acted upon by springs 72 which tend to swing them inwardly. By means of this construction, the governor arms by centrifugal action will advance the cam disk 32 circumferentially of the shaft 6, and consequently will time the start of the engagement of the braking surfaces in accordance with the speed of the shaft so that the shaft will be uniformly stopped at a predetermined point in its rotation irrespective of the speed thereof when the stopping mechanism is thrown in.

60 While it is preferred to employ the construction and arrangement of parts shown and described, it will be understood that this construction and arrangement is not essential except so far as specified in the appended claims.

65 What is claimed as new is:—

1. A stop mechanism having, in combination, a driven member, a driving mechanism therefor, means under the control of the operator for throwing out the driving mechanism at a point in the rotation of the driven member dependent upon the speed of the driven member, and means for stopping the rotation of the driven member after the driving mechanism is thrown out.

2. A stop mechanism having, in combination, a driven member, driving mechanism therefor, means for stopping the rotation of the driven member after the driving mech-

anism is thrown out, and means under the control of the operator and timed by the driven member for throwing out the driving mechanism a substantial interval before the driven member is stopped.

3. A stop mechanism having, in combination, a driven member, driving mechanism therefor, means under the control of the operator and timed by the driven member for throwing out the driving mechanism at a point in the rotation of the driven member, and means for stopping the rotation of the driven member rendered active a predetermined degree of rotation after the driving mechanism is thrown out.

4. A stop mechanism having, in combination, a driven member, driving mechanism therefor, means controlled by the speed of the driven member for throwing out the driving mechanism, and means for stopping the driven member rendered active a predetermined degree of rotation after the driving mechanism is thrown out.

5. A stop mechanism having, in combination, a shaft, a driving mechanism therefor, a brake for reducing the speed of the shaft, means for applying the brake, and means including a cam for throwing out the driving mechanism and for varying the timing of the application of the brake in accordance with the speed of the shaft.

6. A stop mechanism having, in combination, a driven member, a driving mechanism therefor, means under the control of the operator and timed by the driven member for throwing out the driving mechanism at a point in the rotation of the driven member, and cam controlled means for stopping the rotation of the driven member rendered active a predetermined degree of rotation after the driving mechanism is thrown out.

7. A stop mechanism having, in combination, a driven member, a driving mechanism therefor, means comprising a cam for throwing out the driving mechanism, means for varying the timing of the cam in accordance with the speed of the driven member, and means for stopping the rotation of the driven member after the driving mechanism is thrown out.

8. A stop mechanism having, in combination, a driven member, a driving mechanism therefor, a brake for reducing the speed of the driven member, means controlled by the speed of the driven member for throwing out the driving mechanism, and means for applying the brake a predetermined degree of rotation after the driving mechanism is thrown out.

9. A stop mechanism having, in combination, a driven member, driving mechanism therefor, means for throwing out the driving mechanism whereupon the driven member is actuated by its own momentum, a

brake for the driven member, and means for applying the brake at the completion of a predetermined degree of rotation of the driven member by its own momentum.

10. A stop mechanism having, in combination, a driven shaft, speed reducing mechanism therefor, a cam for controlling the effective operation of the speed reducing mechanism, and a second cam mounted on the shaft for rendering the operation of said first cam effective.

11. A stop mechanism having, in combination, a driven shaft, speed reducing mechanism therefor, a cam for controlling the effective operation of the speed reducing mechanism, a second cam for rendering the operation of said first cam effective, and means for varying the timing of said second cam in accordance with the speed of the shaft.

12. A stop mechanism having, in combination, a driven shaft, speed reducing mechanism therefor, a cam and a cooperating cam roll for controlling the effective operation of the speed reducing mechanism, a latch for maintaining the cam and cam roll out of engagement, and means for releasing the latch at a predetermined number of degrees of rotation of the driven shaft before the start of the effective operation of the speed reducing mechanism whereby the cam and cam roll are rendered active.

13. A stop mechanism having, in combination, a driven shaft, a speed reducing mechanism therefor, a latch for maintaining the speed reducing mechanism out of operation, a disk mounted on the shaft, a cam carried by the disk for releasing the latch, a second cam carried by the disk for controlling the effective operation of the speed reducing mechanism when the latch is released, and means for adjusting the disk circumferentially of the shaft to vary the timing of the cams in accordance with the speed of the shaft.

14. A stop mechanism having, in combination, a driven shaft, speed reducing mechanism therefor, a cam for controlling the effective operation of the speed reducing mechanism, a second cam for rendering the operation of said first cam effective, and governor controlled means for simultaneously varying the timing of the two cams in accordance with the speed of the shaft.

15. A stop mechanism having, in combination, a driven shaft, a brake therefor, a disk mounted on the shaft, a cam carried by the disk for controlling the effective operation of the brake, a second cam carried by the disk for rendering the operation of said first cam effective, a member secured to the shaft, centrifugal governor arms pivoted on said member secured to the shaft, and links connecting the governor arms with the disk whereby the disk is adjusted circumferen-

4

tially of the shaft to vary the timing of the cams in accordance with the speed of the shaft.

16. A stop mechanism having, in combination, a driven member, driving mechanism therefor, means for stopping the rotation of the driven member after the driv-

ing mechanism is thrown out, and means for throwing out the driving mechanism a pre-determined number of degrees of rotation ¹⁰ of the driven member before the driven member is stopped irrespective of the speed of the driven member.

ALFRED B. FOWLER.
